(57) **CLAIM**

We claim the ornamental design for a fishing hook, as shown and described.

DESCRIPTION

FIG. 1 is a perspective view of a fishing hook, showing a first embodiment of our new design;

FIG. 2 is a right-side elevational view of FIG. 1;
FIG. 3 is a left-side elevational view of FIG. 1;
FIG. 4 is a front elevational view of FIG. 1;
FIG. 5 is a rear elevational view of FIG. 1;
FIG. 6 is a top plan view of FIG. 1;
FIG. 7 is a bottom plan view of FIG. 1;
FIG. 8 is a perspective view of a second embodiment thereof;
FIG. 9 is a left-side elevational view of FIG. 8;
FIG. 10 is a right-side elevational view of FIG. 8;
FIG. 11 is a front elevational view of FIG. 8;
FIG. 12 is a rear elevational view of FIG. 8;
FIG. 13 is a top plan view of FIG. 8;
FIG. 14 is a bottom plan view of FIG. 8;
FIG. 15 is a perspective view of a third embodiment thereof;
FIG. 16 is a right-side elevational view of FIG. 15;
FIG. 17 is a left-side elevational view of FIG. 15;
FIG. 18 is a front elevational view of FIG. 15;
FIG. 19 is a rear elevational view of FIG. 15;
FIG. 20 is a top plan view of FIG. 15;
FIG. 21 is a bottom plan view of FIG. 15;
FIG. 22 is a perspective view of a fourth embodiment thereof;
FIG. 23 is a left-side elevational view of FIG. 22;
FIG. 24 is a right-side elevational view of FIG. 22;
FIG. 25 is a front elevational view of FIG. 22;
FIG. 26 is a rear elevational view of FIG. 22;
FIG. 27 is a top plan view of FIG. 22;
FIG. 28 is a bottom plan view of FIG. 22;
FIG. 29 is a perspective view of a fourth embodiment thereof;
FIG. 30 is a front elevational view of FIG. 29;
FIG. 31 is a rear elevational view of FIG. 29;
FIG. 32 is a left-side elevational view of FIG. 29, the right-side elevational view being a mirror image thereof;
FIG. 33 is a top plan view of FIG. 29; and,
FIG. 34 is a bottom plan view of FIG. 29.
The broken lines in the figures depict portions of the fishing hook that form no part of the claimed design.
